U.S. PATENT DOCUMENTS

D283,130 S 3/1986 Boenning
D297,222 S 8/1988 Rauch*Primary Examiner* — George D Kirschbaum**CLAIM**

The ornamental design for a doorbell, as shown and described.

DESCRIPTION

FIG. 1 is a front, side, and top perspective view of a doorbell embodying the new design.

FIG. 2 is a back, side, and bottom perspective view thereof.

FIG. 3 is a front view thereof.

FIG. 4 is a back view thereof.

FIG. 5 is a first side view thereof.

FIG. 6 is a second side view thereof.

FIG. 7 is a top view thereof; and,

FIG. 8 is a bottom view thereof.

The broken line showing is included for the purpose of illustrating portions of the “article” and forms no part of the claimed design. The dash-dot-dash lines represent the boundary of the claim.
